UNITED STATES PATENT OFFICE.

FRED W. SAKON, OF JOHNSTOWN, PENNSYLVANIA.

TIE.

1,413,433.

Specification of Letters Patent. Patented Apr. 18, 1922.

Application filed August 29, 1921. Serial No. 496,409.

To all whom it may concern:

Be it known that I, FRED W. SAKON, a citizen of the United States, residing at Johnstown, in the county of Cambria and State of Pennsylvania, have invented new and useful Improvements in Ties, of which the following is a specification.

This invention comprehends the provision of a railroad tie, which is constructed of wood and metal for the purpose of affording the tie maximum strength and to materially prolong the life of the tie.

More specifically stated, the invention is made up of an intermediate, wooden section and metallic end sections upon which the rails are supported, the metallic end sections being designed to receive the adjacent end of the wooden sections and associated therewith in a manner to prevent relative movement between the sections.

Another object of the invention resides in the novel construction of means for securing the metallic end sections to the wooden section with a view of holding the sections fixed relatively.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views and wherein:

Figure 1 is a side elevation of the tie, partly in section, showing one embodiment of the invention.

Figure 2 is a top plan view.

Figure 3 is a transverse sectional view through one of the metallic sections.

Figure 4 is a detail view of one of the wedges utilized in securing the metallic sections to the wooden sections.

Figure 5 is a fragmentary longitudinal section through a modified construction.

Figure 6 is a view similar to Figure 1 of a further modified form.

Figure 7 is a top plan view of Figure 6.

Figure 8 is a transverse sectional view through one of the metallic sections.

Figure 9 is an enlarged fragmentary sectional view showing the manner of connecting one of the metallic sections with the wooden section of the tie.

Figure 10 is a view of the rail fastening means.

Referring to the drawings in detail, 10 indicates the wooden section of the tie and which section is arranged between the metallic end sections 11. The wooden section 10 is much longer than the metallic sections 11, the latter being designed to receive the ends of the intermediate wooden section 10. 60 As illustrated in Figures 1 to 3 inclusive, each metallic section is hollow and of rectangular formation in cross section, including an end wall 12 against which the adjacent end of the wooden section 10 bears 65 when the sections are operatively associated. The metallic section 11 is formed with an extension 13 which projects beyond the end wall 12 in the direction of the wooden section 10; and this extension is also of substantially rectangular formation in cross section, 70 inasmuch as it is designed to receive the adjacent end of the wooden section 10. 75 As illustrated in Figure 1, the wooden section 10 has its ends reduced as at 14 thus defining a shoulder 15 which is engaged by the extension 13 of the metallic section when the parts are operatively associated. The reduced extremity 14 is of a size to be easily fitted within the extension 13 when the parts 80 are initially associated. By use of the wedged shaped elements 16 the wooden and metallic sections are held fixed relatively

when the sections are simultaneously associated for use. In other words, the wedge 85 shaped elements 16 are first driven a slight distance in each end of the wooden section 10; after which the metallic sections are arranged in end to end relation with the wooden section 10. The metallic sections 11 are 90 then forced upon the ends of the wooden section by hydraulic pressure or any other suitable means, incident to which the wedge shaped elements 16 are forced wholly within the ends of the wooden section, spreading 100 the latter so as to frictionally engage the walls of the extension 13 of the metallic sections. Consequently, the ends of the wooden sections 10 are wedged within the metallic sections 11, so that the respective 105 sections are held fixed relatively. The rails 17 are supported by the metallic sections 11 and are clamped thereto by any suitable fastening means indicated at 18. As above stated, the metallic sections are hollow, but 110 are reinforced and properly strengthened by reinforcing elements 19 which as illustrated

in Figure 3, which are arranged within the corners of the metallic sections 11. The construction of the tie is such that it can be manufactured at a nominal cost, and at the same time possesses maximum strength with a view of prolonging the life of the tie as compared to the wooden tie now in use.

In Figure 5, I have illustrated a modified form of the invention, wherein the intermediate wooden section is indicated at 20 and the metallic end sections at 21. The metallic sections are of the same construction as the sections 11 above described being reinforced by corner elements 22, and also formed with extensions 23 designed to receive the reduced extremities 24 of the wooden section. However, in this form of the invention the metallic section 21 is held rigidly associated with the intermediate wooden section 20 by means of a rod 25 and wedges 16'. This rod 25 passes longitudinally through the wooden section 20 and also through the adjacent walls of the metallic sections as shown. The rod 20 is provided with a head 26 which bears against the adjacent end wall of one of the metallic end sections, while a nut 27 associated with said rod bears against the corresponding end wall of the other metallic section.

In Figures 6 to 9 inclusive, I have illustrated a further modified form of the invention wherein the intermediate wooden section is indicated at 28 and the metallic end sections at 29. In this form of the invention, each metallic section includes a hollow portion of substantially rectangular formation in cross section open at one end to receive the reduced extremity 30 of the wooden section 28 in the same manner described in connection with the preferred form of the invention illustrated in Figures 1 to 3. This portion of the metallic sections bears against the shoulder 31 defined by the reduced extremities 30, while the metallic sections 29 are held rigidly associated with the wooden section 28 by means of the wedge shaped elements 32. These wedged shaped elements are forced into the wooden section 28 during the association of the metallic sections with the wooden sections as hereinafter described. This form of the invention varies from the preferred form illustrated in Figures 1 and 3, in that

each metallic section 29 includes a portion 33 which is substantially I-shaped in cross section as illustrated in Figure 8. The rails 34 are supported by the portions 33 of the metallic sections and secured thereto by suitable fastening elements 35.

In Figure 10, I have illustrated an improved fastening means for the rails 36, and which means includes a plate 37 formed with a lug 38 on the underside thereof and which lug is received by a recess 39 formed in the tie to prevent turning of the fastening plate with relation to the tie. The plate is secured to the tie by means of a bolt 40.

While it is believed that from the foregoing description the nature and advantages of the invention will be readily apparent. I desire to have it understood that I do not limit myself to what is herein shown and described, and that such changes may be resorted to when desired as fall within the scope of what is claimed.

What I claim is:—

1. A railroad tie comprising a wooden intermediate section, and metallic end sections, said metallic sections being designed to receive the extremities of the wooden section, said extremities of the wooden section being reduced, and wedge shaped elements adapted to be driven into the wooden section incident to the association of the latter with the metallic sections, whereby said sections are held fixed relatively. 80

2. A railroad tie comprising an intermediate wooden section and metallic end sections, said metallic sections being designed to receive the adjacent ends of the wooden section, each metallic section including a wall adapted to bear against the adjacent end of the wooden section, and means for holding said sections fixed relatively. 90

3. A railroad tie comprising an intermediate section, and metallic end sections, said metallic sections being designed to receive the adjacent ends of the wooden section, said metallic sections also including portions of I-shaped formation in cross section, and means for holding the respective sections fixed relatively. 100

In testimony whereof I affix my signature.

FRED W. SAKON.
